US0D1087359S

(12) **United States Design Patent** (10) **Patent No.:** **US D1,087,359 S**
(45) **Date of Patent:** **** Aug. 5, 2025**

(54) **NECK PROTECTOR**

(71) Applicant: **Wenwen Zeng**, Guangdong (CN)

(72) Inventor: **Wenwen Zeng**, Guangdong (CN)

(73) Assignee: **Shenzhen Meidu Intelligent Technology Co., Ltd.**, Shenzhen (CN)

(**) Term: **15 Years**

(21) Appl. No.: **29/926,258**

(22) Filed: **Jan. 30, 2024**

(30) **Foreign Application Priority Data**

Aug. 3, 2023 (CN) 202330492115.7

(51) LOC (15) Cl. **24-04**

(52) U.S. Cl.

USPC **D24/191; D29/101.2**

(57) **CLAIM**

The ornamental design for a neck protector, as shown and described.

DESCRIPTION

FIG. 1 is a perspective view of a neck protector showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is an enlarged detail view of area 9 shown in FIG. 1; and,

FIG. 10 is an enlarged detail view of area 10 shown in FIG. 1.

The broken lines in the drawings depict portions of the neck protector that form no part of the claimed design.

1 Claim, 10 Drawing Sheets
